IRVIN K. KREIDER, OF LANCASTER, PENNSYLVANIA

SILO ELEVATOR

Application filed May 14, 1928. Serial No. 277,474.

The object of this invention is to provide an ensilage carrier including a body adapted to be received by the frame of an elevating device movable vertically along the wall of a silo, the body being detachable from the frame for mounting on a truck by means of which the material is carried to the feeding trough.

A further object is to provide a particular form of counter balanced frame, with braking means therefor, and a body having a hinged end wall constituting a closure for the body when the latter is mounted on the truck, and forming a platform for the operator when said body is in vertical position on the elevator frame.

With the foregoing and other objects in view, the invention consists in the novel construction and arrangement of elements described, illustrated and claimed, it being understood that modifications may be made within the scope of the claim without departing from the spirit of the invention.

In the drawings forming part of this application: —

Figure 1 is a view in elevation showing a silo with a vertical track on one side thereof, and showing the counter balanced frame mounting a detachable body or receptacle for the ensilage.

Figure 2 is a view in elevation showing the frame, from one side thereof, and showing the body in the frame and also in side elevation.

Figure 3 is a detail view, taken on line 3—3 of Figure 1, and constituting a section thru the body and the track structure, with a portion of the wall of a silo.

Figure 4 shows the frame in rear elevation, and illustrates especially the construction and operation of the braking devices.

Figure 5 is a detail in section showing elements referred to below.

Figure 6 is a plan view of the body, one end portion, constituting a swinging closure being illustrated in dotted lines as in open position.

Figure 7 is a section on line 7—7 of Figure 1, showing the mounting of the track structure and showing elements of the ladder.

Figure 8 illustrates the body and truck in side elevation.

Figure 9 is a bottom plan view of the truck.

Figure 10 is a detail in section on line 10—10 of Figure 9.

Figure 11 is a detail in section on line 11—11 of Figure 9.

The wall of the silo is designated 10, and carried thereby are rails 11 and 12 retained in position by brackets or other suitable securing devices 13, shown in this case as being in the form of transverse bars with outwardly turned ends. The elements embedded in the wall and serving as the rungs of a ladder are designated 14.

An upper pulley wheel or sheave 15 accommodates a cable 16 connected with the counterbalance 17, and this cable has connection by means of a stirrup or the like 18 with a rectangular or other suitable frame 20 by means of which the detachable body is carried.

This body is shown in detail in Figure 8 where it appears in elevation, and it is further shown in plan in Figure 6 and in section in Figure 3. One end portion of the body, constituting a permanent end thereof is designated 21, and the other end 22 forms a closure or door, mounted at 23 for swinging movement and facilitating the loading and unloading operation, said door also constituting a platform for the operator when the body is positioned on the carrier as in Figure 1, the frame 20 constituting the principal element of the carrier.

This frame 20 may include a lower outwardly deflected portion 20' adapted for engagement by an angle bar 24 on end member 21. The body is readily detachable from the rectangular inclosing and hoisting frame or carrier 20, because in Figure 2 the only engagement at the bottom is at 20', 24, and at the top or elsewhere any well known securing devices such as hooks (one of which is shown conventionally), may be employed.

Carried by the frame is a vertical guide and brake rail 26 mounted in a fixed position as at 27, and a rail 28 is movably mounted by means of pin and slot connection shown

at 29, the rail last named being movable on transverse bars 30 and 31 of the frame. Brackets such as 32 are secured in any suitable manner and bars 33, passed loosely thru apertured portions of these brackets, are encircled by springs 34.

The bars 33 are secured at 35 to the guide rail 28, and the springs exert outward pressure under normal conditions, so that the 10 brake rail and guide rail 28 is normally in condition to act as a brake as the frame operates vertically along the rails 11 and 12. A suitable brake lining is shown conventionally at 39.

15 In order to operate the movable brake rail 28 and release the latter from its normal contact with the adjacent stationary track rail, I provide a plurality of levers one of which is designated 40 and is pivotally connected with element 26 at the point 41, and is further connected by means of a pin or bolt 42 with a lug 43 on lever 44. This element last named is pivoted at 45 to movable brake member 28 and the upward movement of the 20 right hand end of lever 44 in Figure 4, by means of the operating rod 46, produces the release movement of the brake element 28. It will be observed that the handle member 47 connected with rod 46 is in such position 25 that it will be easily accessible to the operator when standing on platform 22 of the body or receptacle, which element 22 constitutes a closure when the receptacle is being used as a truck, as for instance in Figure 8.

30 In order to supply convenient means for transporting the material from the silo to the feeding trough, I employ the receptacle previously used in removing the material from the silo, and mount this receptacle or body on a frame constituting a truck frame, or merely a truck, this device being mounted on a plurality of wheels such as those shown at 50, 51, 52, the wheels being of the caster variety and carried by elements or bolsters 35 54 and 55 which in turn form a part of the truck structure.

35 This structure includes side elements 56 and 57. However, any suitable truck may be employed, but in order that the body may be 40 properly retained it is desirable to mount the body on the truck in the manner shown in Figure 10 in which I have illustrated a plurality of inverted channel elements 60 and 61 connected with the rear bolster by means 45 of bolts or the like 62 and spaced to receive therebetween one flange of an angle element 63 carried by the body.

50 The structure of Figure 2 is raised from the position of Figure 1, when empty, by the counterbalance 17, or may be so raised, and when the container or body is loaded with material withdrawn from the silo, it will descend because heavier than the weight. Control is secured by the brake mechanism of 55 Figure 4, a movable rail at the left cooperat-

ing with a stationary vertical guide. The operator standing on the upper end of the body when the latter is vertically positioned, operates brake handle 47. After the body is lowered, it is released from carrier or frame 70 20, and may be placed on the truck of Figures 8, 9, and 10, and moved to the feeding trough. Any desired number of hooks of the kind shown conventionally in Figure 2, provide securing and releasing means between the body 75 and the frame 20.

The end member 22 having previously served as a platform for the operator, is opened as in Figure 8, and forms a discharge member when tilted to lower position. 80

Having described the invention what is claimed is:—

In a device of the class described, a frame, means for counter balancing the frame, a stationary guiding element carried by the frame, 85 a movable guiding element carried by the frame, this guiding element constituting a rail effective along one edge thereof as a brake, resilient means bearing on the movable element and tending to force it outwardly, and a plurality of pivotally connected levers, one of which is pivotally connected with the stationary guiding element, the other lever being pivotally connected with the movable guiding element, means for pivoting the 90 levers together at a point between the ends of the lever connected with the movable element and operable for shifting said movable element inwardly and outwardly with reference to the stationary guiding element, while 100 maintaining parallel relation therewith.

In testimony whereof I affix my signature.

IRVIN K. KREIDER.
